DESIGN FOR A TOY VEHICLE OR THE LIKE

Walter Baetz, New York, N. Y.

Application April 25, 1935, Serial No. 56,545

Term of patent 7 years

To all whom it may concern:

Be it known that I, Walter Baetz, a citizen of the United States of America, and a resident of New York, in the county of New York and State of New York, have invented a new, original, and ornamental Design for Toy Vehicles or the like, of which the following is a specification, reference being had to the accompanying drawing, forming a part hereof.

In the drawing:
Fig 1 is a top plan view of the toy vehicle or the like; and

Fig. 2 is a side elevational view of the same.

I claim:

The ornamental design for a toy vehicle or the like as shown.

WALTER BAETZ.
